FUSE.

1,022,329.

Specification of Letters Patent.

Patented Apr. 2, 1912.

Application filed December 15, 1909. Serial No. 533,279.

To all whom it may concern:

Be it known that we, FREDERICK P. POOLE and PAUL A. BRENDL, both citizens of the United States of America, and residing at 5 Bridgeport, in the county of Fairfield and State of Connecticut, have invented a certain new and Improved Fuse, of which the following is a specification.

Our invention relates to fuse plugs and 10 the object of our invention is to provide an improved type of plug of small size adapted to carry a heavy current without danger of explosion on the blowing of the fuse.

In the accompanying drawings, Figure 1 15 is a plan of a fuse plug with cap removed, embodying our improvement; Fig. 2 is a vertical section through the same with cap on; and Fig. 3 is a plan of a plug with cap removed and showing a barrier of modified 20 form.

Describing our invention with relation to the embodiment thereof illustrated, our improved fuse comprises a hollow insulating body A with screw shell and center contacts B and C respectively, of common type, and a cap D. Instead of employing a fuse strip extending from the center contact to the shell and united to the latter in a single well, we propose to form a plurality of wells 25 *a* in the body A and carry a series of fuse strips from the center contact into these wells. In the examples illustrated two wells are shown diametrically opposite each other, and the series of fuses F is formed 30 from a continuous flat metallic strip bent down at the middle and soldered to the center contact and provided with calibration holes *f* one on either side of the center contact. Obviously the current capacity of the 35 plug is the sum of the capacities of the fuse strips since the current passes from the shell to the center contact through all the strips of the series simultaneously. Upon the blowing of the fuse it is found that an 40 explosion of much less violence results when a series of such fuse strips is employed than when a single strip of greater current ca-

pacity is inserted between the shell and the center contact, and that a porcelain body of given strength remains uninjured in the one 50 case whereas it is frequently shattered in the other. The explanation of this is thought to be found in the succession of small explosions occurring when a series of strips is employed, since the capacity of the 55 strips varies slightly, either accidentally or intentionally. The improved result when a series of strips is employed is furthered if a barrier G be inserted between the strips so that each explosion is confined to a separate 60 chamber. This barrier may be formed in any desired manner. A simple method is shown namely by forming grooves *g* in the body A in which the edges of the barrier G may engage. The precise form and 65 nature of the barrier is immaterial, it being shown as a thick wall in Fig. 1 and as a relatively thin partition in Fig. 3.

Obviously the number and form of the 70 fuse strips and the manner of their fastening and form of the barrier may be varied in many ways without departing from the scope of our invention, and we do not limit ourselves to the precise structure shown.

We claim as our invention:

1. A fuse having shell and center contacts, in combination with an inclosed fuse strip having its opposite ends electrically connected with the shell and being electrically connected with the center contact at 80 a point intermediate said ends, together with a barrier interposed between said ends to form separate fuse chambers therefor.

2. A plug fuse having shell and center contact, a central well and a plurality of lateral wells, and a plurality of inclosed fuse members extending between and permanently connected to said shell and center contacts through said central and lateral wells, for the purpose described.

3. A plug fuse having shell and center contact, a central well and a plurality of lateral wells, and a plurality of inclosed fuse members extending between and per-

manently connected to said shell and center contacts through said central and lateral wells, in combination with barrier means arranged in said central well and serving to confine the rupture points of said fuse members in separate chambers, for the purpose described.

In testimony whereof we have signed our

name to this specification, in the presence of two subscribing witnesses.

FREDERICK P. POOLE.
PAUL A. BRENDL.
